UNITED STATES PATENT OFFICE.

SIDNEY R. M. MALLOCH, OF PHILADELPHIA, PENNSYLVANIA.

COLLAPSIBLE SHIPPING CRATE.

Application filed March 8, 1922. Serial No. 540,737.

To all whom it may concern:

Be it known that SIDNEY R. M. MALLOCH, a citizen of the United States of America, residing at Philadelphia, in the county of Philadelphia and State of Pennsylvania, has invented new and useful Improvements in Collapsible Shipping Crates, of which the following is a specification.

The object of the invention is to provide a simple, comparatively inexpensive and efficient shipping crate for fowls and farm products which may be readily folded into compact form for return shipment to the producer and wherein all of the parts thereof are permanently connected whether extended for use or folded for return shipment to the end that the loss or misplacement of any of the elements thereof may be avoided; and with these objects in view the invention consists in a construction and combination of parts of which a preferred embodiment is shown in the accompanying drawings, wherein:

Figure 1 is a perspective view of a crate embodying the invention, the same being extended or set up for use.

Figure 2 is a longitudinal sectional view of the same.

Figure 3 is a transverse sectional view thereof.

Figure 4 is a perspective view of the crate in its folded condition.

Figure 5 is a horizontal detail sectional view of one of the corner joints to show the means of locking the side and end walls in their operative relations.

The crate consists essentially of the top and bottom walls 10 and 11 of which the latter may be sunken to form a suitable floor, side walls 12 respectively of unitary or one-piece construction and end walls 13 of horizontally divided two-piece or sectional construction with the upper and lower members thereof hingedly connected as indicated at 14, and respectively jointed to the top and bottom walls by hinges 15 and 16. Strips 17 are arranged at the ends of the bottom wall to raise the hinges 16 so as to provide a space for the reception of the side walls 12 which are hingedly connected at their lower edges as at 18 to the bottom wall.

The hinges of the side walls are arranged to permit of the inward folding of the latter into positions which in a crate of the dimensions herein shown are adapted to lie in a common plane parallel with the bottom wall,

and the end walls are constructed and mounted to fold inwardly on top of the side walls, with the adjacent edges of their sections adapted to break so that the upper and lower members of each end wall lie in parallelism and substantial contact.

The side edges of the top wall are provided with depending stop pins 19 to limit the outward swinging movement of the upper edges of the side walls, the latter preferably having depressions or sockets 20 for the reception of said pins, and secured to the inner surfaces of the upper sections of the end walls adjacent to the joints controlled by the hinges 14 are latches 21 shown clearly in Figure 5 and consisting of spring tongues having offsets or shoulders 22 to bear against the inner surfaces of the side walls to prevent inward collapsing thereof and terminal tongues 23 to bear against the end edges of the side walls to prevent inward collapsing of the end walls. These tongues preferably extend outward far enough to permit of the extremities thereof being grasped or engaged by the fingers to retract the latches sufficiently to disengage the shoulders 22 thereof from the inner surfaces of the side walls so that the latter may be folded inwardly when it is desired to collapse the crate.

Owing to the location and construction of the latches 21 it is obvious that in setting up the crate from a folded position it is only necessary to raise the top wall to separate it from the bottom wall sufficiently to permit the end walls to assume a vertical position or with the centers thereof in a common plane and then to fold the side walls outwardly until the movement thereof is checked by the stop pins 19. This movement of the side walls will repress the latches 21 until the end edges of the side walls pass the shoulders 22 whereupon the latches will spring outward and lock both side and end walls in their operative positions. In collapsing the crate it is only necessary to deflect the latches by outward pressure upon the extremities of the tongues 23 sufficiently to release the end edges of the side walls so that the latter may be folded inwardly whereupon the side walls will be released and will be free to buckle inwardly to permit the dropping of the top wall to the folded position indicated in Figure 4.

The top wall is preferably provided with a door or gate 24 having spring hinges 25

and stop pins 26 to limit the closing movement thereof, in order that access may be had to the interior of the crate to insert or remove the contents thereof.

- 5 Having described the invention, what is claimed as new and useful is:—
1. A collapsible shipping crate having top, bottom, side and end walls of which the side walls are hingedly mounted upon the bottom wall for inward folding movement and the end walls are of sectional construction 30 and consist of upper and lower sections jointed at their meeting edges for inward folding movement, the remote edges of the end wall sections being hingedly connected respectively with the top and bottom walls, 35 and locking means at the meeting edges of the side and end walls for preventing inward swinging movement thereto, and consisting of spring latches mounted upon the end walls near the joint between the sections 40 thereof and provided with shoulders for bearing against the inner surfaces of the side walls and tongues for bearing against the end edges of the side walls, said tongues being extended to form finger holds accessible from the interior of the crate for disengaging the latches from the side walls.

2. A collapsible shipping crate having top, bottom, side and end walls of which the side walls are hingedly mounted upon the bottom wall for inward folding movement and the end walls are of sectional construction 30 and consist of upper and lower sections jointed at their meeting edges for inward folding movement, the remote edges of the end wall sections being hingedly connected respectively with the top and bottom walls, 35 and locking means at the meeting edges of the side and end walls for preventing inward swinging movement thereto, and consisting of spring latches mounted upon the end walls near the joint between the sections 40 thereof and provided with shoulders for bearing against the inner surfaces of the side walls and tongues for bearing against the end edges of the side walls, said tongues being extended to form finger holds accessible from the interior of the crate for disengaging the latches from the side walls.

In testimony whereof he affixes his signature.

SIDNEY R. M. MALLOCH.
